US00D628169S

(12) **United States Design Patent**
Yamada

(10) **Patent No.:** **US D628,169 S**
(45) **Date of Patent:** **** Nov. 30, 2010**

(54) **LIGHT EMITTING DIODE MODULE**

(75) Inventor: **Motokazu Yamada**, Tokushima (JP)

(73) Assignee: **Nichia Corporation**, Tokushima (JP)

(**) Term: **14 Years**

(21) Appl. No.: **29/366,756**

(22) Filed: **Jul. 29, 2010**

(57) **CLAIM**

The ornamental design for a light emitting diode module, as shown and described.

DESCRIPTION

FIG. 1 is a front elevational view of a light emitting diode module in accordance with a first embodiment of my new design;

FIG. 2 is a top plan view of the light emitting diode module in accordance with the first embodiment of my new design;

FIG. 3 is a bottom plan view of the light emitting diode module in accordance with the first embodiment of my new design;

FIG. 4 is a left side elevational view of the light emitting diode module in accordance with the first embodiment of my new design; and,

FIG. 5 is a right side elevational view of the light emitting diode module in accordance with the first embodiment of my new design.

The broken line showing of environment (the remaining structure of the light emitting diode module) in FIGS. 1-5 are for illustrative purposes only and forms no part of the claimed design.

The diagonal line shading illustrates a transparent portion of the light emitting diode module.

The bottom plan view of the light emitting diode module is omitted because the bottom surface of the light emitting diode module is flat and devoid of surface ornamentation.
